UNITED STATES PATENT OFFICE.

JAMES BRACE, OF DETROIT, MICHIGAN.

DESIGN FOR A LAMP.

45,100.

Specification for Design.

Patented Jan. 6, 1914.

Application filed August 14, 1913. Serial No. 784,784. Term of patent 3½ years.

To all whom it may concern:

Be it known that I, JAMES BRACE, a citizen of the United States of America, residing at Detroit, in the county of Wayne and State of Michigan, have invented a new, original, and ornamental Design for a Lamp, of which the following is a specification, reference being had therein to the accompanying drawing, forming part thereof.

view of a lamp showing my new design; and Fig. 2 is an upper end elevation of the same.

I claim:

The ornamental design for a lamp, as shown.

JAMES BRACE.
